UNITED STATES PATENT OFFICE

2,533,820

DETECTING EQUIPMENT

Louis J. La Marca, Portsmouth, N. H.

Application November 18, 1946, Serial No. 710,654

3 Claims. (Cl. 177—371)

1

This invention relates to detecting equipment and more particularly to equipment for use in connection with signalling devices, such as fire alarms, for obtaining or preserving evidence of the presence and identity of a person operating the signalling device.

Heretofore it has been proposed to provide photographic equipment arranged to take a picture of a person operating a fire alarm device. The proposed photographic equipment was designed especially for being coordinated only with a particular type of alarm device, and could not easily be operatively associated with other alarm devices.

An object of this invention is to provide detecting equipment of the general character referred to which may be manufactured as standard units of basically uniform design, but which may easily be adapted for being cooperatively associated with any of a number of signalling devices of different sizes and shapes.

Another object of the invention is to provide novel equipment of the kind described which includes a simple and rugged enclosure structure containing photograph taking apparatus.

A further object of the invention is to provide equipment including such an enclosure structure and means for easily securing the structure to a support, for example, a post carrying a fire alarm box.

Other objects will become apparent from a reading of the following description, the appended claims, and the accompanying drawings in which:

Figure 1 is a side elevational view of equipment embodying the invention arranged in cooperative relationship to a fire alarm box;

Figure 2 is a vertical section on the line 2—2 of Figure 1;

Figure 3 is a fragmentary vertical section on the line 3—3 of Figure 4, drawn on an enlarged scale as compared to Figures 1 and 2;

Figure 4 is a horizontal sectional view on the line 4—4 of Figure 1;

Figure 5 is a front elevation of the equipment shown in Figures 1 and 2; and

Figure 6 is a wiring diagram.

For the purpose of illustration, the drawings show a preferred form of equipment for use in connection with a signalling device comprising a fire alarm box A mounted on a supporting post B. The alarm box A and post B are shown as being of conventional construction. One of the features of equipment embodying the invention is that it may easily be adapted or modified for

2

being mounted in cooperative association with any of many different types and sizes of alarm or signalling devices.

The equipment shown includes an enclosure structure or cubicle generally designated C including side walls 1 and 2, a top wall 3, bottom 4, and rear wall 5. These parts may be assembled from standard metal parts and welded or otherwise secured together and re-enforced in any approved manner. The front of the enclosure structure C is formed with an entrance opening 6 which normally is closed by a door 7 mounted on hinges 8. The door is not locked and can be opened at any time; but normally is held closed by an automatic closing device 9 of any known or suitable kind.

In accordance with the invention, one wall of the enclosure structure or cubicle C is formed with an opening adapted to receive the signalling device A so as to permit the latter to protrude into the structure C. Signalling devices such as fire alarm boxes in different localities vary as to size and shape. However, equipment embodying the invention may readily be adapted for cooperative positioning with respect to different forms and sizes of signalling devices by merely providing an opening in one of the walls of the enclosure structure C. In the illustrative embodiment, the rear wall 5 is formed with an opening 10 which is conformed to the outline of the fire alarm box A and which is sufficiently large to enable the box A to protrude through the rear wall 5.

Means are provided for easily securing the enclosure structure C to the support or post B. As shown in Figures 1 and 4, two securing structures generally designated 11 and 11 are mounted respectively at the top and bottom of the cubicle C. Each structure 11 comprises two vertically spaced U-shaped straps 12—12, the superposed ends of which are connected by vertical strips 13 and 14. The strip 13 of each securing structure 11 is connected by a hinge 15 to a mounting plate 16 on the back wall 5. When it is desired to position the equipment in cooperative relationship to the box A and post B, the securing structures 11—11 are manipulated or swung counterclockwise, as viewed in Figure 4, about the hinges 15, the cubicle C is then moved into substantially abutting relationship to the post B and the structures 11 are then swung clockwise so as to bring the vertical strips 14 close to the cubicle rear wall 5. The strips 14 are apertured to provide hasp-like members which pass over apertured lugs 17 on the rear wall 5. When the securing structures

11 have been set in the positions shown in Figures 1 and 4, they may be locked in place by padlocks 18 placed on the lugs 17.

The enclosure structure C is provided with equipment for obtaining or preserving evidence of the presence of a person within the structure. Normally, the best legal evidence would be obtained or preserved by restraining or locking the person within the structure C. I prefer to obtain and preserve a photograph of any person entering the enclosure structure C. To this end, the cubicle C is provided with and encloses photograph taking means and means for actuating the latter to take a picture of a person within the cubicle.

In the form shown, the cubicle C is provided with a casing generally designated 19 including a front wall 20, a side wall 21, a bottom 22, and another side wall and top which are common with portions of the cubicle walls 2 and 5. The casing front wall 20 is formed with an opening 23 covered by bullet-proof glass 24 directly in line with a camera 25 mounted within the casing 19 so as to be inaccessible to a person in the cubicle C, and being trained into the cubicle and toward the entrance opening 6. The casing front wall 20 is also formed with an opening 26 covered by bullet-proof glass 27 directly in front of a flash bulb 28 carried by a reflector 29.

Means are provided for operating the camera shutter and touching off the flash bulb in response to a person's entering through the opening 6 in the cubicle C. In the form shown, a solenoid device 29 is arranged to be energized by the closing of a switch 30 mounted within the cubicle C so as to be engaged and actuated by the door 7 when the latter is opened. The solenoid device 29 includes a plunger 31 which is connected to a shutter arm 32 on the camera 25 and to a switch 33, the closing of which lights or touches off the flash bulb 28. Current for operating the solenoid is supplied from line conductors 34 and 35 leading to the primary winding of the transformer 36. A conductor 37 leads from the line 34 through the switch 30 to one end of the primary winding while a conductor 38 leads directly from the line 35 to the other end of the primary winding. Conductors 39 and 40 lead from the ends of the secondary winding of the transformer 36 to the ends of the winding of the solenoid device 29. The conductor 38 also leads through a conductor 41 to one terminal of the flash lamp 23, the other terminal of which leads through a conductor 42 and the switch 33 to the conductor 40.

When a person opens the door 7 to enter the cubicle C, the door engages the switch 30 and closes the latter so as to energize the transformer 36 and solenoid 29 for operating the plunger 31 to actuate the camera shutter arm 32 and close the switch 33. Closing of the switch 33 causes the flash bulb 28 to be touched off so that the camera shutter is opened in properly timed relationship to the flashing of the bulb 28, thus effecting the taking of a picture by the camera 25.

If desired, the cubicle C may be equipped with a flood lamp 43 connected across the supply lines 34, 35 and being adapted to be controlled by a manually operable switch 44.

In accordance with a further feature of the invention, the equipment within the casing 19 may be accessible to authorized persons from outside the cubicle C. To this end, the wall portion common to the casing 19 and the side wall 2 of

the cubicle is formed with an aperture 45 normally closed by a closure member 46 mounted on hinges 47. The closure member is provided with a lock 48; and may be unlocked and opened by an authorized person for providing access to the camera 25 and other equipment within the casing 19 without its being necessary to enter the cubicle C.

The construction shown by way of example embodies the invention in the form now preferred, but it will be understood that changes may be made without departing from the invention as defined in the claims.

I claim:

15. 1. An assembled equipment unit for use in connection with a signalling device mounted on and protruding from a support, said unit consisting of an enclosure structure formed with an opening of a shape and size to receive the signalling device when said enclosure structure is positioned substantially against the support so that the signalling device will protrude through and substantially close said opening and project into said enclosure structure to be housed therewithin; means for securing said enclosure structure to said support when so positioned; an entrance opening in said enclosure structure; a door normally closing said entrance opening; a casing within and fixed to said enclosure structure and having a plurality of walls one of which is constituted by a part of a wall of said enclosure structure; a camera mounted within said casing inaccessibly to a person in said enclosure structure and being aligned to encompass said entrance opening within its view; means mounted within and on said enclosure structure adjacent said entrance opening and being operable in response to opening of said door for automatically actuating said camera; an aperture in said wall part common to said enclosure structure and said casing for providing access to the interior of said casing from the exterior of said enclosure structure; and a lock-equipped closure for said aperture.
2. An assembled equipment unit for use in connection with a signalling device mounted on and protruding from a support, said unit consisting of an enclosure structure formed with an opening of a shape and size to receive the signalling device when said enclosure structure is positioned substantially against the support so that the signalling device will protrude through and substantially close said opening and project into said enclosure structure to be housed therewithin; means for securing said enclosure structure to said support when so positioned, said means comprising a strap, a connection between one end of said strap and said enclosure structure which enables said enclosure structure to be abutted against said support and said strap then swung about said connection to embrace said support with the other end of said strap being close to said enclosure structure, and means for securing said other end of said strap to said enclosure structure; an entrance opening in said enclosure structure; a door normally closing said entrance opening; a casing within and fixed to said enclosure structure and having a plurality of walls one of which is constituted by a part of a wall of said enclosure structure; a camera mounted within said casing inaccessibly to a person in said enclosure structure and being aligned to encompass said entrance opening within its view; means mounted within and on said enclosure structure adjacent said entrance opening and being operable in response to opening of said door for auto-

matically actuating said camera; an aperture in said wall part common to said enclosure structure and said casing for providing access to the interior of said casing from the exterior of said enclosure structure; and a lock-equipped closure for said aperture.

3. An assembled equipment unit for use in connection with a fire alarm box mounted on and protruding from a post, said unit consisting of an enclosure structure formed with an opening of a shape and size to receive the box when said enclosure structure is positioned substantially against the post so that the box will protrude through and substantially close said opening and project into said enclosure structure to be housed therewithin; means for securing said enclosure structure to said post when so positioned, said means comprising a U-shaped strap, a hinge connection between one end of said strap and said enclosure structure which enables said enclosure structure to be abutted against said post and said strap then swung about said hinge connection to embrace said post with the other end of said strap being close to said enclosure structure, and means for securing said other end of said strap to said enclosure structure; an entrance opening in said enclosure structure; a door normally closing said entrance opening; a casing within and fixed to said enclosure structure and having a plurality of walls one of which is constituted by a part of a wall of said enclosure structure; a camera mounted within said casing inaccessibly

5

to a person in said enclosure structure and being aligned to encompass said entrance opening within its view; means mounted within and on said enclosure structure adjacent said entrance opening and being operable in response to opening of said door for automatically actuating said camera; an aperture in said wall part common to said enclosure structure and said casing for providing access to the interior of said casing from the exterior of said enclosure structure; and a lock-equipped closure for said aperture.
